(57) **CLAIM**

The ornamental design for a glass tile with a halo pattern, as shown and described.

DESCRIPTION

FIG. 1 is a perspective view of a design for a glass tile with a halo pattern, as shown and described;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross-sectional view taken along lines 8-8 in FIG. 2 thereof.

The waving oblique shade lines shown in FIG. 3 depict a non-uniformly translucent surface and are not surface ornamentation.
